Patented May 23, 1972

223,652

CASE FOR ART SUPPLIES

Martin A. Jaffe, 3001 Henry Hudson Parkway, Bronx, N.Y. 10463; George S. Northrop, 3200 Hickory St., Wantagh, N.Y. 11793; and Samuel Braun, 75 Greenhaven Road, Rye, N.Y. 10580

Filed Aug. 12, 1970, Ser. No. 24,445

Term of patent 3½ years

Int. Cl. D9—03

U.S. Cl. D9—189

FIG.1

FIG.2

FIG.3

FIG.4

FIG.5

FIG.6

FIG.9

FIG. 7

FIG. 8

FIG. 1 is a front perspective view of a case for art supplies showing our new design with the cover in the open position;

FIG. 2 is a top plan view;

FIG. 3 is a front elevational view;

FIG. 4 is a rear elevational view;

FIG. 5 is a bottom plan view;

FIG. 6 is a side elevational view, the opposite side being the same as the side that is illustrated;

FIG. 7 is a top perspective view thereof with the cover closed;

FIG. 8 is a top perspective view thereof with the cover removed; and

FIG. 9 is a section taken along line 9—9 of FIG. 5.

We claim:

The ornamental design for a case for art supplies, as shown and described.
